(57) **CLAIM**

The ornamental design for a part of an automobile tire, as
shown and described.

DESCRIPTION

FIG. 1 is a perspective view of a part of an automobile tire,
it being understood that the tread pattern repeats uniformly
throughout the circumference of the tire.

FIG. 2 is a front elevation view thereof, a top plan view and
a bottom plan view are identical with the front elevation
view.

FIG. 3 is a rear elevation view thereof.

FIG. 4 is a right side elevation view thereof.

FIG. 5 is a left side elevation view thereof.

FIG. 6 is an enlarged fragmentary front elevation view
thereof; and,

FIG. 7 is a cross-sectional view thereof taken along line
7—7 in FIG. 6.

The broken line showing of a tire sidewall and inner bead is
for illustrative purposes only and forms no part of the
claimed design.
